METHOD AND MACHINE FOR SPINNING ROVINGS

Walter Frenzel, Dresden, Germany

Application October 12, 1953, Serial No. 385,646

8 Claims. (Cl. 57—36)

This invention relates to a method and machine for spinning rovings.

When spinning yarn from fibrous material by applying the drawing process to cotton, worsted and bast fiber spinning it was the usual practice hitherto to employ after the preparatory work one or more roving or fly frames on which the roving was slightly twisted, so that it could be wound on a bobbin while remaining still in drawable condition when introduced into the next drawing frame. On moving into the creel this highly sensitive roving is, however, subject to faulty drafts with the result that cross-sectional variations occur in the finished yarn, which are difficult to avoid. Furthermore, in an ordinary fly frame production is upwardly limited by the maximum spindle speed depending upon the flyer, and the troublesome winding operation requires an intricate mechanical equipment which gets easily out of order. In a cotton fly frame the revolving flyer is unsymmetrical, one leg thereof on which the rotatable presser is arranged being hollow and the other one solid. The differential motion, the pair of cone drums for varying bobbin speed and the motion of the bobbin rail for producing a double cone cop form make the fly frame cumbersome and therefore expensive with respect to both prime cost and operation. Measurements of power requirement disclose an extraordinarily low efficiency, since only about 13 percent of operating power was found to be used for spinning and the remaining 87 percent for keeping the machinery going.

The twisting of the roving interferes with spinning on the next fly frame in so far as between front and back rollers not only preliminary drafting has to take place but also untwisting to a certain extent to insure proper subsequent drafting. The twist of the roving exerts also some influence upon the reach between the drawing rollers and the division of the total draft into partial drafts of the drawing frame. Such a fly frame requires therefore careful adjustment and supervision of its parts as well as special attendance. There are numerous sources of trouble to be found in a fly frame of this type, which endanger the production of good readily drawable roving uniform as to twist and cross section.

It is the object of the invention to eliminate the above-mentioned drawbacks of fly frames by simplifying their construction and at the same time considerably increasing their output. This object is attained by giving the roving having been drafted on a fly frame a hard twist which renders it undrawable, winding it on a bobbin, preferably of the double-flanged type, and then, for further treatment on a spinning machine, untwisting the roving directly before it enters the feed rollers of the drawing frame by means of a thread gripper revolving in a direction opposite to that of the twist until the roving becomes drawable again. The twist may be removed completely or in some cases just sufficiently enough to hold the roving together during drawing. When horn-like and not particularly pliable fibers, as bast, wool, synthetic fibers, and the like, are handled, it may be ad-

2

visable after complete untwisting to add a few turns in the opposite direction to straighten such fibers out. While in this fully controllable condition and immediately after having been untwisted in front of the feed rollers of the drawing frame of the next passage or spinning machine the roving is drawn in by them. If the twisting and untwisting members are driven by worm wheels the roving or intermediate yarn will receive a perfectly uniform twist which may be completely taken out again in the same way.

Owing to its greater strength, this hard-twisted undrawable roving can be wound on ordinary double-flanged bobbins in cylindrically parallel layers without involving the risk of cross-sectional variations. Upon removal of the bobbin from the fly frame, the bobbin is reversed end for end through 180°, whereupon the bobbin is passed in the reversed position to the spinning machine to be untwisted again.

The spinning machine for carrying out the method according to the invention is fitted in front of the roving feeding means of the drawing frame with a thread brake or gripper comprising for instance a pair of plate springs driven in a direction opposite to that of the twist of the yarn and forming a passage for the roving, and with a yarn guiding arm encircling the winding bobbin at the same speed as the gripper. The roving conducted to the gripping point retains therefore its undrawability up to and into this gripping zone, untwisting occurring only on the very short free section between the thread gripper and the gripping zone of the pair of feed rollers. In the machine according to the invention this section may be made shorter than the medium length of the yarn fiber to prevent faulty draft due to the pull exerted by the drawing frame. A thread gripper forming a tapering 35 rotary cone may be operating only a few millimeters away from the gripping zone of the rollers.

Although the cost of a spinning frame according to the invention will be somewhat higher due to the provision of the simple untwisting means in front of the drawing frame, the fly frame, on the other hand, will not need any more an equipment which as at present raises its manufacturing cost, lowers the quality of the yarn and limits output. The fly frame may be replaced for example by a simple flyer of known type or by a ring 45 spinning member so as to considerably accelerate spindle speed and thus not only compensate loss in delivery due to the hard twist of the roving but to increase production up to about 50 percent in some instances. The omission of the bobbin driving means, the differential and conoidal 50 gearings for the variable rail lift, and the presser device simplifies the fly frame and reduces its cost.

The invention affords the further advantage of permitting additional drawing of any yarn produced on a fly or spinning frame by simply taking out the twist thereof 55 prior to the transfer to the drawing frame.

One embodiment of the invention is illustrated in the accompanying drawing, wherein

Figure 1 is a diagrammatic view of the rear part of a fly frame during winding of the roving;

Fig. 2, a view of the front part of a spinning machine when the roving is transferred to the drawing frame; and

Fig. 3 shows a modification.

In the fly frame shown in Fig. 1 the sliver 2 drawn by the frame 1 passes through the bore 3 of the flyer spindle 4 driven in the direction of the arrow by the worm wheel drive 5 to the stationary flanged bobbin 6 on which it is wound up in parallel layers. The flyer spindle 4 disposed in the bearing 4a imparts to the roving 2a formed of the sliver 2 sufficient twist to render it undrawable. The bobbin 6 rests on the dead spindle 7 the lower portion of which may be provided with a bobbin drag 7a, so that the roving can be wound on the bobbin 6 without

any risk of cross-sectional reductions of the yarn due to increased tensile stress. The construction of this part of the fly frame is therefore simplified, rendered less expensive and requires not so much power.

The spinning machine, shown in Fig. 2, for further drawing is provided with a flyer member 4 arranged directly in front of the pair of feed rollers 8a of the drawing frame 8 in the bearing 4a, and driven by a worm wheel drive 5. Upon removal of the bobbin 6 carrying the roving 2a, placed from the spindle 7 of the fly frame shown in Fig. 1, the bobbin 6 is reversed end for end through 180° so that its flange a takes the position previously occupied by its flange b and vice versa, whereupon the bobbin 6 is on the spindle 7 of the fly frame shown in Fig. 2, so that the roving 2a moving from the bobbin 6 along the flyer 4 and through the bore 3 passes between the springy sides of the tapering thread gripper 9 secured to the top end of the flyer spindle 4. Owing to the gripping of the roving 2a by the gripper 9 and owing to the rotation of the flyer spindle 4 and the gripper 9 secured thereto in opposite direction to the direction of rotation of the flyer spindle 4 of the fly frame shown in Fig. 1, twist is fully or almost so taken out of the roving 2a, depending on the degree of twist received, along the short distance between the thread gripper 9 and the feed rollers 8a, which distance is shorter than the medium length of the yarn fiber. In this drawable condition the roving is then cautiously introduced into the drawing frame for further treatment. Hence it follows that even coarser yarns, as finished weft yarns, may still be further drawn and spun into finer yarns by removing again their twist. Instead of the flyer 4 a ring spinning member may be used.

In the modification shown in Fig. 3 the bobbin 6 lies on a higher plane than the drawing means of the frame (not shown). The thread guide 103 supporting the flyer 104 and the thread gripper 109 comprises two parts connected by bevel gears 110. The drive 105 can be disconnected by a clutch 111. This arrangement permits better utilization of the machine space.

Comparative experiments disclosed the further advantage of an improvement of the quality of the finished thread. Breaking length values, for instance, were found to be more favorable and those for unevenness decreased due to the fact that the hard-twisted roving had not been subjected to any drawing and was drafted and spun in twistless condition. The number of thread breakages was extraordinarily low.

I claim:

1. A method for spinning slivers, comprising the steps of: drawing out a sliver on a fly frame so as to form a roving, subjecting said roving to a hard twist so as to render same undrawable and winding simultaneously the

twisted roving on a bobbin, thereafter untwisting the roving for returning same into drawable condition by means of gripping means rotating in a direction opposite to the direction of the twist, and carrying out said untwisting shortly before the roving enters the feed rollers of the drawing frame.

2. A method for spinning slivers as claimed in claim 1, wherein said untwisting of the roving by said gripping means takes place at a distance from said feed rollers shorter than the medium length of the yarn fibers of the roving.

3. A method for spinning slivers, as claimed in claim 1, wherein said roving is almost entirely untwisted by said gripping means.

4. A method for spinning slivers as claimed in claim 1, wherein said roving is completely untwisted by said gripping means.

5. In a method for spinning slivers as claimed in claim 1, the steps of completely untwisting the roving and adding a few turns of twist in the opposite direction.

6. In a spinning machine having a drawing frame and feeding means for feeding a roving thereto, a spindle arranged for receiving a bobbin on which twisted roving is wound and from which it is fed to the drawing frame, a flyer rotatable about said spindle and bobbin mounted thereon and having means to guide the roving from the bobbin to the feeding means, rotatable gripping means for gripping said roving disposed directly before the feeding means, and driving means cooperating with said flyer and said roving gripping means to rotate the same at equal speeds.

7. In a spinning machine as claimed in claim 6, said rotatable gripping means being rigidly connected with said flyer.

8. In a spinning machine as in claim 6, said roving gripping means including a series of plate springs, said plate springs being formed in a tapering passage to guide, grip and untwist the roving as it is fed from the bobbin to the feeding means.
